UNITED STATES PATENT OFFICE.

JOHN F. BARNHART, OF AKRON, OHIO.

DESIGN FOR A COMBINATION PENHOLDER AND PAPER KNIFE OR SIMILAR ARTICLE.

Application filed April 4, 1929. Serial No. 30,758. Term of patent 14 years.

To all whom it may concern:

Be it known that I, JOHN F. BARNHART, a citizen of the United States, and a resident of Akron, county of Summit, and State of Ohio, have invented a new, original, and ornamental Design for a Combination Penholder and Paper Knife or Similar Article, of which the following is a specification, reference being had to the accompanying drawings, forming a part thereof.

In the drawings,

Figure 1 is a front view of a combination penholder and paper knife or similar article showing my new design; and

I claim:

The ornamental design for a combination penholder and paper knife or similar article as shown.

JOHN F. BARNHART.
